UNITED STATES PATENT OFFICE.

EDWARD H. WHEELER, OF HARTFORD, CONNECTICUT.

BUCKLE.

1,268,412.

Specification of Letters Patent. Patented June 4, 1918.

Application filed June 22, 1917. Serial No. 176,372.

To all whom it may concern:

Be it known that I, EDWARD H. WHEELER, a citizen of the United States, residing at Hartford, in the county of Hartford, and State of Connecticut, have invented certain new and useful Improvements in Buckles, of which the following is a specification.

This invention relates to improvements in buckles, more particularly to devices of this character adapted for use for securing the straps of overshoes, raincoats and the like, and has for one of its objects to simplify and improve the construction and increase the efficiency and utility of devices of this character.

Another object of the invention is to provide a device of this character which may be readily adjusted to adapt it to shoes and other garments of various sizes, and to likewise adapt the garment to the size of the person of the wearer, and without detaching any of the parts.

With these and other objects in view, the invention consists in certain novel features of construction, as hereinafter shown and described and then specifically pointed out in the claims; and in the drawings illustrative of the preferred embodiment of the invention.

Figure 1 is a plan view of one of the improved buckles in closed position;

Fig. 2 is a longitudinal section on the line 2—2 of Fig. 1 without the straps;

Fig. 3 is a detached perspective view of the body or base portion;

Fig. 4 represents detached perspective views of the members comprising the locking clasp portion of the device;

Fig. 5 represents detached perspective views of a modified construction of the locking clasp portion of the device.

The improved device comprises a body or base portion 10, preferably curved longitudinally and with a relatively large opening or eye 11 at one end and formed into alternating openings 12 and transverse bars 13. The openings extend only a part of the distance transversely of the body 10 leaving longitudinally directed portions 14 at the sides. The side edges of the body 10 are preferably directed outwardly to form side guards or ribs 15. A strap 16 is connected to the terminal opening 12 at one end of the body, the strap being secured in any suitable manner to the shoe, coat or other gar-

ment to which the device is applied, the latter not shown as it forms no part of the present invention.

The bars 13 between the apertures 12 provide means for supporting a suitable clasp device to which another strap 17 is attached, the latter being attached to the garment at the opposite side to the strap 16. The clasp device is formed in two coacting parts, a body portion bent intermediate its ends to form spaced sides 18—19, the side 18 having longitudinally directed clefts 20 whereby tongues 21, 22, and 23 are produced. The intermediate tongue 22 extends beyond the tongues 21 and is bent laterally of the body 10 to form a relatively long loop 24. The portion 19 of the clasp body is reduced at one end, the reduced portion turned into an eye 25, the eye corresponding in length to the width of the tongue 24. The other portion 26 of the clasp comprises a plate 26 having an opening 27 to receive the strap 17 and with a transverse bar 28 spaced from the other end, the latter being slightly rounded to be engaged by the eye 25 of the portion 19 of the clasp body. The terminals 29—30 of the plate 26 in advance of the bar 28 are slightly curved and are adapted to engage respectively with the tongues 21—23. The tongue 24 is slightly less in width than the lengths of the openings 12 of the body 10 and is designed to engage through the openings one at a time, while the tongues 21—23 operate over the unperforated portions 14 of the body 10 and next to the guard ribs 15. The portions 29—30 extending in advance of the bar 28 providing a locking means whereby the clasp device is yieldably coupled to the body 10.

When the buckle device is to be applied the body 10 which is attached to the strap 16 is placed against the body of the garment to which it is attached and the body portion 18—19 of the clasp turned over toward the plate 26. This disposes the point of the hook or loop member 24 above the outer face of the body 10, and the requisite strain is applied to the strap 17 to place the hook or loop 24 opposite one of the openings 12. The body portion of the clasp is then forced over into parallel relation to the body 10, which movement causes the terminals 29—30 to apply a considerable strain against the tongues 21—22 and pass between them and the side portions 14 of the body 10, this

movement likewise causing the hook or loop 24 to pass through the adjacent opening 12 and around the nearest transverse bar 13. The clasp device being constructed of resilient material such as tempered steel, exerts a sufficient force against the terminals 29—30 of the plate 26 to retain the clasp device in position upon the body portion 10, and prevent the accidental displacement between 10 the parts and likewise maintain the requisite strain upon the straps.

In Fig. 5 a slight modification in the manner of constructing the clasp device is shown. In the modified structure the body 15 portion of the clasp is constructed with a strap receiving aperture 31 and spaced clefths 32 whereby tongues 33—34—35 are produced. The tongue portions 33 are bent at their free ends into eyes 37—38, while the 20 central tongue 34 extends in advance of the eyes. The portion just described corresponds substantially to the member 18—19, while the part which corresponds to the plate 26 comprises a plate 39 reduced at 25 one end and the reduced portion bent upon itself to form a loop 40 and the bent-over portion extended into a hook or loop 41, which corresponds to the hook or loop 24. Spurs 42—43 extend from the reduced portion 30 of the member 39 to engage in the eyes 37, the spurs being spaced from the portion 40, so that when the body member 33 containing the tongue 34 is rotated upon the spurs 42—43, the elongated portion 40 engages the tongue 34 and thus performs the 35 same function as the terminal 29—30 of the plate 26.

All of the parts of the improved buckle are pressed or struck from sheet metal, preferably steel, and can be inexpensively manufactured entirely by machinery, thus practically eliminating manual operations. The guard ribs 15 protect the clasp members, and likewise prevent the clasp members from 45 coming in contact with surrounding objects. The guard ribs 15 likewise strengthen and stiffen the body 10, thus enabling the latter to be constructed from thinner metal than would otherwise be possible.

50 It will be noted that in form of the structure shown in Figs. 1, 2 and 3, that the portion 44 of the hook 24 is disposed rearwardly of the eye 25, thus materially reducing the sweep of the hook.

55 The base portion of the buckle is curved longitudinally to conform to the transverse curvature of the shoe with which it is associated, and the clasp members when closed lie flat upon the base, thus producing a relatively thin buckle with no projecting parts to catch upon the clothing.

Having thus described the invention, what is claimed as new is:

1. A buckle comprising a base member adapted to support a holding strap having 65 longitudinally directed lands at the sides and a plurality of transverse bars in spaced relation between the lands, and a clasp device including a body having longitudinally directed clefths to produce a plurality of resilient tongues and a locking member rotatably engaging said body member and including projections engaging said tongues and a hook engaging one of said bars, another holding strap being adapted to be 75 connected to said clasp device.

2. A buckle comprising a base member adapted to support a holding strap having a plurality of transverse bars in spaced relation, and a clasp device including a body 80 having longitudinally directed clefths to produce a plurality of resilient tongues and a locking member rotatably engaging said body member and including projections engaging said tongues and a hook engaging 85 one of said bars, another holding strap being adapted to be connected to said clasp device.

3. A buckle comprising a base member adapted to support a holding strap having 90 outturned guard ribs at the sides and a plurality of transverse bars in spaced relation, and a clasp device including a body having longitudinally directed clefths to produce a plurality of resilient tongues and a locking member 95 rotatably engaging said body member and including projections engaging said tongues and a hook engaging one of said bars, said clasp device bearing upon the body between the guard ribs and another holding strap adapted to be connected to said clasp device.

4. A buckle comprising a base member adapted to support a holding strap having longitudinally directed lands at the sides 105 and a plurality of transverse bars in spaced relation between the lands, and a clasp device including a body folded intermediate the ends to produce coacting portions extending face to face, one of said coacting portions terminating in an eye and the other coacting portion having longitudinally directed clefths to produce an intermediate tongue and outer tongue with the intermediate tongues extended into a hook to 110 engage said bars one at a time, and a locking member including a bar to engage said eye and projections to engage said outer tongues.

115 In testimony whereof I affix my signature.

EDWARD H. WHEELER. [L. S.]
